[57] CLAIM

The ornamental design for a combined toy bucket and tools therefor, substantially as shown and described.

DESCRIPTION

FIG. 1 is a perspective view of a combined toy bucket and tools therefor showing our new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a right side elevational view, the left side elevational view is a mirror image thereof.
